UNITED STATES PATENT OFFICE

172,856

GAS BURNER

Robert A. Wittmann, Chicago, Ill., assignor to
Hardwicke Stove Company, a corporation of
Delaware

Application January 6, 1953, Serial No. 23,032

Term of patent 14 years

(Cl. D81—10)

To all whom it may concern:

Be it known that I, Robert A. Wittmann, a citizen of the United States, residing at Chicago, State of Illinois, have invented a new, original, and ornamental Design for a Gas Burner, of which the following is a specification, reference being as to the accompanying drawing, forming a part hereof.

Figure 1 is a top plan view showing my new design for a gas burner;

Figure 2 is a side elevation of the same;

Figure 3 is a bottom plan view of the same;

Figure 4 is a front view of the same; and
Figure 5 is a rear view of the same.

I claim:

The ornamental design for a gas burner, substantially as shown.

Certificate of Correction

Design No. 172,856

August 17, 1954

Robert A. Wittmann

It is hereby certified that error appears in the above numbered patent requiring correction as follows:

In the grant, lines 2 and 13, and in the heading to the printed specification, line 4, name of assignee, for "Hardwicke Stove Company", each occurrence, read *Hardwick Stove Company*;

and that the said Letters Patent should be read as corrected above.

Signed and sealed this 21st day of September, A. D. 1954.

[SEAL]

DAPHNE LEEDS,
Assistant Commissioner of Patents.
